UNITED STATES PATENT OFFICE.

ALBERT SYVERSON AND CORNELIUS SYVERSON, OF PELICAN RAPIDS,
MINNESOTA.

COMB-CLEANER.

SPECIFICATION forming part of Letters Patent No. 694,040, dated February 25, 1902.

Application filed February 19, 1901. Serial No. 47,993. (No model.)

To all whom it may concern:

Be it known that we, ALBERT SYVERSON and CORNELIUS SYVERSON, citizens of the United States, residing at Pelican Rapids, in ⁵ the county of Ottertail and State of Minnesota, have invented a new and useful Comb-Cleaner, of which the following is a specification.

This invention relates to cleaners for combs; ¹⁰ and it has for its object to provide a construction that will be carried upon the comb at all times in such position as not to interfere with the operation of the comb and which when it is to be used may be operated with efficient ¹⁵ results, a further object of the invention being to provide a cheap and simple latching means that will hold the cleaner in its inoperative position against accidental dislodgment.

²⁰ Additional objects and advantages of the invention will be apparent from the following description.

In the drawings, forming a portion of this specification, and in which like numerals of ²⁵ reference indicate similar parts in the several views, Figure 1 is a perspective view showing a comb provided with the improved cleaner, said cleaner being raised to its inoperative position. Fig. 2 is a side elevation showing ³⁰ one end portion of the comb. Fig. 3 is a transverse section through the comb and its cleaner with the latching mechanism in its engaging position. Fig. 4 is a side elevation of one end portion of the comb and showing the ³⁵ cleaner lowered to the ends of the teeth and shown in section.

Referring now to the drawings, there is shown a comb comprising a back portion 5, having heavy end teeth 6 and 7 and smaller ⁴⁰ or narrower intermediate teeth 8, of usual form and spacing. The end teeth 6 and 7 have slots 9 and 10 formed transversely therethrough and extending longitudinally thereof, and in these two slots are slidably engaged pins 11 and 12, which are passed therethrough and connect two strips 13 and 14, which are disposed against the opposite side faces of the teeth of the comb, whereby when

⁵⁰ either strip is moved toward or away from the back 5 the other strip will be moved with it and neither strip can be moved entirely from engagement with the comb.

To clean out the matter that accumulates between the teeth of the comb the strips 13 and 14 are connected by cross-pieces 16, one ⁵⁵ of which lies between each pair of teeth of the comb, and thus when the strips 13 and 14 are moved from their positions against the back of the comb, as shown in Fig. 1, to the free ends of the teeth these cross-pieces engage and clear out all matter that may be lodged between the teeth. After the teeth have been cleaned by thus moving the cleaner to the free ends thereof the cleaner is moved back into position against the back 5 of the ⁶⁰ comb, and to hold the cleaner in this position a latch or locking mechanism is provided. This latch consists of two fingers 18 and 19, which are pivotally mounted upon the strips ⁶⁵ 13 and 14 at diametrically opposite points of the strips. A groove 20 is formed transversely ⁷⁰ of the back of the comb, and these two fingers are bent into angular shape, so that they may be moved pivotally to engage the groove and to overlap with their free ends. To hold the free ⁷⁵ ends in their overlapping positions, balls 22 and 23 are formed upon the ends thereof, and these balls are adapted to lie one behind the other, the extremities of the fingers being bent upwardly and laterally, as shown, so that they ⁸⁰ may entwine. When the fingers are thus engaged, they lie in the groove 20 and are held against lateral movement such as would disengage the extremities of the fingers by the side walls of the groove. By grasping the two ⁸⁵ balls, however, and giving them a twisting motion they may be disengaged one from behind the other, after which the fingers may be swung outwardly to free the back of the comb. When the fingers are engaged over ⁹⁰ the back of the comb, they of course prevent movement of the cleaner; but when disengaged the cleaner may be moved at will.

It will be understood that in practice various modifications of the specific construction ⁹⁵ shown may be made and that any suitable

materials and proportions may be used for the various parts without departing from the spirit of the invention.

What is claimed is—

- 5 A comb having its end teeth formed with slots and its back with laterally-projecting flanges provided with transversely - alined grooves, in combination with a cleaning device adapted normally to bear against the under sides of the flanges and comprising two strips connected intermediate of their ends by cross-pieces to fit closely between the teeth and at their terminals by pins disposed to work in the said slots, and locking means carried by

the strips and comprising resilient arms having their intermediate portions disposed to engage the said grooves and their terminals provided with balls or knobs to interlock over the back, substantially as and for the purpose specified.

In testimony that we claim the foregoing as our own we have hereto affixed our signatures in the presence of two witnesses.

ALBERT SYVERSON.
CORNELIUS SYVERSON.
